DESIGN FOR A LIPSTICK CASE

Ralph P. Lewis, Scarsdale, N. Y., assignor to Harriet Hubbard Ayer, Inc., New York, N. Y., a corporation of New York

Application September 24, 1948, Serial No. 148,760

Term of patent 7 years

(Cl. D86—10)

To all whom it may concern:

Be it known that I, Ralph P. Lewis, a citizen of the United States, residing at 17 Colvin Road, Scarsdale, New York, have invented a new, original, and ornamental Design for Lipstick Case, of which the following is a specification, reference being had to the accompanying drawing, forming a part thereof. In the drawing:

Fig. 1 is a perspective view, showing the lipstick case with the cap applied thereto in closed position; and

Fig. 2 is a perspective view, showing the lipstick case with the cap telescoped thereon while the end of the case is open for projection of the lipstick.

I claim:

The ornamental design for a lipstick case, as shown.

RALPH P. LEWIS.
